United States Patent Office.

ALBERT JOHNSON AND SYDNEY E. ALLEN, OF RALEIGH, NORTH CAROLINA.

Letters Patent No. 60,897, dated January 1, 1867.

IMPROVED ALARM GUN.

The Schedule referred to in these Letters Patent and making part of the same.

TO ALL WHOM IT MAY CONCERN:

Be it known that we, ALBERT JOHNSON and SYDNEY E. ALLEN, of Raleigh, in the county of Wake, and State of North Carolina, have invented a new and improved Alarm Gun; and we do hereby declare that the following is a full, clear, and exact description thereof, which will enable others skilled in the art to make and use the same, reference being had to the accompanying drawings, forming part of this specification.

The present invention relates to a new and improved alarm gun with which persons may be warned of the approach of burglars or thieves, the gun being susceptible of being so set or adjusted as to fire in any direction.

In the accompanying plate of drawings, my improved alarm gun is illustrated—

Figure 1, being a side elevation of view of our improved alarm gun; and

Figure 2, a plan or top view of the same.

Similar letters of reference indicate like parts.

A in the drawings represents the support for the alarm, consisting of a three-armed base, B, provided with a centre upright socket, C; D, the gun barrel, provided with a trunnion pin or stud, E, upon its under side, at such point of its length as will cause it to be evenly balanced. By this trunnion pin the gun barrel turns in the upper end of the socket upright, C. F, the nipple of the gun barrel D. This nipple is upon the upper side of the barrel over its point of support or suspension in the upright C. H, a hammer block, secured to the outer end, I, of a spring-arm, J, attached by its other end, K, to the upper end of the post L secured to the base plate B at the outer end of one of three arms. To the under side of the spring-arm J, between its point of attachment to the post L, and its hammer block H, a trigger-arm, M, is secured, which, when the hammer is to be adjusted for operation, is placed over or set upon the upper edge of the projecting arm, P, of the gun barrel D. Q, an arm secured to upper side of gun barrel, across the point where the nipple is attached, which arm extends across the gun barrel projecting from each side of the same, with such end of the same as projects over the arm, P, of the gun barrel provided with an opening, T, in the same, to allow the trigger-arm M to be set upon said barrel-arm P. In the use of my improved alarm gun, constructed as above described, after the gun barrel is loaded it is first set by the prongs, V, of its base, in the most desirable position for operation; when, setting the trigger-arm M upon the gun-arm P, it is ready for operation, or, in other words, the gun hammer "cocked," so that if the gun barrel, by its cross-arm Q, be swung upon upright C, the hammer will be tripped by such arm acting upon the trigger M, and thus the hammer set free to fall upon the nipple of the gun barrel, and thereby, through the percussion cap placed upon it, the contents of the gun barrel will be discharged, producing the desired alarm.

From the above description of my improved alarm, it is plainly obvious that if a gun be used having several barrels pointing in opposite and various directions, by changing either one or more of the said barrels the gun can be thus adjusted to discharge in any desired direction.

Having thus described our invention, we claim as new, and desire to secure by Letters Patent—

The base A, gun barrel D, spring hammer and trigger-arm J, and arms P and Q attached to barrel, when all constructed and combined together, substantially as and for the purpose described.

The above specification of our invention signed by us this second day of November, 1866.

ALBERT JOHNSON,
SYDNEY E. ALLEN.
